(57) **CLAIM**

The ornamental design for a video processing unit for a visual prosthetic apparatus, as shown and described.

DESCRIPTION

This invention was made with government support under grant No. R24EY12893-01 awarded by the National Institutes of Health. The government has certain rights in the invention.

FIG. 1 is a top view of the video processing unit.

FIG. 2 is a first perspective view, from the top, front and right side, of the video processing unit.

FIG. 3 is a second perspective view, from the top, the rear and the left side, of the video processing unit; and,

FIG. 4 is a third perspective view, from the top and the left side, of the video processing unit.

1 Claim, 4 Drawing Sheets

FIG. 1

FIG. 2

FIG. 3

FIG. 4
